United States Patent Office

Des. 178,669
Patented Sept. 4, 1956

178,669

DRILL PRESS OR SIMILAR ARTICLE

Ingvar O. Johansson, Skokie, Ill.

Application December 23, 1955, Serial No. 39,465

Term of patent 14 years

(Cl. D63—1)

Fig. 1 is a front perspective of a drill press or similar article, showing my new design.

Fig. 2 is a rear perspective thereof.

The dominant features of my design reside in the portions shown in full lines.

I claim:

The ornamental design for drill press or similar article, substantially as shown and described.
